UNITED STATES PATENT OFFICE.

WILLIAM M. GENTLE, OF GREENWOOD, INDIANA.

CARBURETER.

993,516.

Specification of Letters Patent. Patented May 30, 1911.

Application filed December 2, 1909. Serial No. 531,022.

To all whom it may concern:

Be it known that I, WILLIAM M. GENTLE, of Greenwood, county of Johnson, and State of Indiana, have invented a certain new and useful Carbureter; and I do hereby declare that the following is a full, clear, and exact description thereof, reference being had to the accompanying drawings.

The object of this invention is to provide a carbureter that will produce a uniform mixture of air and vaporized fuel for the engine while the speed is increasing or decreasing, and in that connection I provide an automatic means for regulating the intake of air and vaporized fuel so that a desired uniformity of mixture is maintained. In explosive engines where the air and fuel are mixed before they are introduced into the cylinder, it is necessary that a nearly uniform ratio of the two be maintained to develop satisfactory power either at high or low speed.

The invention will be understood from the accompanying drawings and the following description and claims.

In the drawings Figure 1 is a central vertical section through the carbureter in idle condition, the control lever being in position to direct all the air through the mixing chamber. Fig. 2 is a section on the line 2—2 of Fig. 1, and partially broken away. Fig. 3 is the same as Fig. 1 with the position of the control lever altered and the air passing through the carbureter, as indicated by arrows. Fig. 4 is a section on the line 4—4 of Fig. 1. Fig. 5 is a plan view of the device.

In detail I provide a bowl 10 open at the top and having a tubular vertical interior wall 11 which is integral with the base of the bowl and extends upwardly therefrom, and which is open at the top and bottom, thereby forming an air passageway. The upper part of the bowl 10 is threaded to receive the threaded portion of the casing 12, which forms the mixing chamber 13 and the top of the bowl 10. The casing 12 has a central downwardly extending tubular portion 14 that surrounds the air tube 11 but is spaced away from it slightly to form a passageway 15, through which liquid fuel may pass from the bowl to the mixing chamber. As seen in the drawings, the tubular port 14 does not reach the bottom of the bowl 10 to permit free access of the fluid to the passageway 15. On one side of the bowl 10 and integral with it is the valve casing 16 for the fuel

inlet valve 17. The stem of the valve 17 extends upwardly through a partition wall 18 in the casing 16, and at its upper end is capped to retain the spring 19, which normally holds the valve 17 open. A valve seat 20 is threaded and screwed into the bottom of the casing 16 with a port 120 through it in position to be closed by the valve 17. A liquid fuel supply pipe 21 is screwed into the base of the valve seat 20. A fuel passageway 22 leads through the partition 18 into the chamber of the bowl 10. The bowl is provided with the usual float 24 secured to one end of the lever 25, which is fulcrumed near the center on the pin 26. The other end of the lever 25 is threaded to receive the adjustable screw 27. By means of the float and the mechanism just described, a predetermined amount of liquid is admitted and maintained in the bowl.

A tubular extension 28 is integral with the casing 12 and extends upwardly therefrom and is threaded at its upper end to receive the tubular valve casing 29. The latter is turned at right angles to the pipe 28 and one end 40 is the air inlet, and the other a passageway to the intake port of the engine cylinder through pipe 30.

In the center of the valve casing 29 a valve 32 is pivoted at its upper end by a pin 33 and depends therefrom at an inclination, so that gravity tends to close it, and also a spring 34 tends to hold it closed. It extends across the passageway to the intake pipe 30, and, therefore, performs somewhat the function of the usual throttle valve, although it is automatic and not manipulated. It opens upwardly toward the intake pipe 30 and closes downwardly against an annular seat that is formed by contracting the passageway through the casing 39 to some extent, see Fig. 3. One end of said spring 34 is connected with the valve 32, and the other end to the adjustable screw 35 in the casing 29.

In the upper part of the casing 29 there is an air inlet opening over the valve 32, which has an area substantially equal to the transverse area of the passageway leading from the throttle valve and which is closed by a valve 36, and which might be termed the "relief" or "back-firing" opening and valve. It is horizontally disposed and is pivoted at one end on the pin 37 to the upper part of the casing 29, and is held down and closed by a flat spring 38, which is secured

at one end by screws to the casing 29 and at the other end extends through the space between the valve 36 and the strap 136 on the underside of the valve. On the occasion of back firing, the back rush of gas would close the valve 32 and open the valve 36 to the dotted line position.

The secondary air inlet 40 is at one end of the casing 29 opposite the intake pipe 30, 10 with the valve located midway between said ends of the casing 29. The transverse area of the air inlet 40 is preferably less, about one-fourth less, than the area of the intake pipe 30, so that some air will always pass 15 up through and from the main air inlet 11 below, or at least this is true while the device is operating normally and the valve 32 is open and until the valve 36 is opened. The air inlet 40 is controlled by a butterfly 20 valve 41 on a pin 42 mounted transversely in one end of the casing 29. There is a lever 43 on one end of the pin 42 for actuating the valve 41. On the other end of the pin 42 there is a finger 44 adapted to engage the 25 ear 45 on one edge of the valve 36 to open it, see Figs. 4 and 5, and the dotted-line position in Fig. 3. The lever 43 may be operated by any suitable connection therewith.

The upper surface of the tubular air inlet 30 11 is ground to fit the under surface of the disk-like valve 46, which is secured to the stem 47. The latter is slidably mounted in the bearings 48 and 49. The bearing 49 is a spider secured to the wall 11. The bearing 35 48 is adjustably mounted in the spider 50, which is secured in the extension 28. The lower end of the bearing 48 has a head 51 which engages one end of the spring 52. The other end of the spring rests upon the 40 upper surface of the valve 46 and tends to hold the valve closed. Secured to the edge of the disk 46 there is a tubular wire fabric 53, which extends downwardly about the air inlet 11 and through the passageway to a 45 point near the bottom of the bowl 10. The fabric is adapted to move upwardly and downwardly with the opening and closing of the valve 46. I do not desire to be limited to a tubular fabric, as any means such as 50 vertical wires, or the like, may operate to accomplish the same purpose.

In operation, the engine is started with the valves of the carbureter in the position shown in Fig. 1. Suction from the piston 55 opens the valves 32 and 46, the springs 34 and 52 being of slight resistance. As the air valve 41 is closed, all the air taken into the cylinder must pass through the fluid saturated screen 53, whereby the fluid becomes 60 vaporized and the air charged. As the valve 46 tends to reseat after each stroke of the piston, it can be readily seen that the screen will be kept moist. As indicated by the arrows in Fig. 3, the air passing through 65 the screen 53 strikes the lower surface of the

casing 12 and moves toward the center of the chamber 13, thereby making a very thorough mixture of the vaporized liquid and air. This movement of the air tends to draw the liquid from the passageway 15 and disperse 70 it through the air. With the valves maintained in this position, the engine would immediately run to the maximum power. The power may be reduced, however, by opening the air valve 41, whereby more air and less 75 vaporized liquid will be taken into the cylinder. As seen in Fig. 3, the outside air passing through the port 40 mixes with the air passing through the carbureter. The engine may be stopped by moving the control lever 43 from the position shown in full lines in Fig. 3 to the position shown by dotted lines, which will cause the finger 44 to engage the ear 45 of the valve 36, whereby 80 the valve is opened. The inrushing air 85 through the valve 36 will keep the valve 32 closed, which will cause the engine to stop for lack of fuel. By this construction of my carbureter it will be readily seen that I maintain any desired proportion of mixture 90 with but slight resistance to the stroke of the piston.

What I claim as my invention and desire to secure by Letters Patent is:

1. A carbureter including means for supplying and mixing air and fuel to form an explosive gas, a casing through which the explosive gas passes from the carbureter, a valve extending across said passageway that tends to open under the influence of the suction of the engine, means tending to close said valve, an opening in said casing to the outer air in advance of said valve, a valve for closing said opening that is pivoted on the side of the valve toward the outlet to 100 the carbureter so that back-firing will tend to open said last-mentioned valve, and yielding means for holding said valve normally closed.

2. A carbureter including means for supplying and mixing air and fuel to form an explosive gas, a casing through which the explosive gas passes from the carbureter, a valve extending across said passageway that tends to open under the influence of the suction of the engine, means tending to close said valve, an opening in said casing to the outer air in advance of said valve, a valve for closing said opening that is pivoted on the side of the valve toward the outlet to 105 the carbureter so that back-firing will tend to open said last-mentioned valve, a spring secured inside of said casing with one end loosely engaging the inner side of said valve, and a strap on the under side of said valve 110 loosely surrounding said spring so that the spring will normally hold the valve closed.

3. A carbureter including means for supplying and mixing air and fuel to form an explosive gas, a casing through which the 115

explosive gas passes from the carbureter, a valve in said casing closing the passageway therethrough that is mounted at one side of the casing so that the other end will be free 5 to open under the influence of the suction of the engine, yielding means for holding said valve normally closed, an opening to the outer air in the wall of said casing in advance of the valve and adjacent the hinged 10 portion of the valve so that as said valve opens its movable portion will tend to move toward said opening, a valve for closing said opening that is pivoted at its side opposite the pivotal point of said first-mentioned 15 valve, so that the free portion of said second valve will be nearer the hinged portion of said first valve, and yielding means for holding the second valve closed, whereby backfiring will tend to simultaneously close the 20 first valve and open the second.

4. A carbureter including means for supplying and mixing air and fuel to form an explosive gas, a casing through which explosive gas passes from the carbureter which 25 has an outlet end and an opposite air inlet end, a valve closing and opening the passageway of the gas through said casing, yielding means tending to hold the valve closed, a valve for controlling the air inlet 30 end of said casing through which air can enter the casing before it passes said first valve, an opening to the outer air in the cas-

ing in advance of said first valve, a valve for closing said opening, means tending to hold said third valve closed, and a single positive 35 means for opening both said second and third valves simultaneously.

5. A carbureter including means for supplying and mixing air and fuel to form an explosive gas, a casing through which explosive gas passes from the carbureter which 40 has an outlet end and an opposite air inlet end, a valve closing and opening the passageway of the gas through said casing, yielding means tending to hold the valve 45 closed, a valve for controlling the air inlet end of said casing through which air can enter the casing before it passes said first valve, an opening to the outer air in the casing in advance of said first valve, a valve for closing 50 said opening, means tending to hold said third valve closed, a single positive means for opening both said second and third valves simultaneously, said opening means being so arranged that it will not open the 55 third valve until after the second valve has been partially opened.

In witness whereof, I have hereunto affixed my signature in the presence of the witnesses herein named.

WILLIAM M. GENTLE.
